(57) **CLAIM**

I claim the ornamental design for a handheld electronic
device, as shown and described.

DESCRIPTION

FIG. 1 is a perspective view of a handheld electronic device
in accordance with the new design of the present application;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in FIGS. 1-7 showing an electronic viewing
screen and a user button switch are for illustrative
purposes only and form no part of the claimed invention.
The design is not limited to the exact details shown in
the drawings, since equivalents and colorable imitations thereof
will be evident to a person of ordinary skill in the art. Thus,
within the scope of the appended claim, which is intended to
cover only the ornamental and novel elements shown in
the drawings, the invention may be practiced otherwise than as
specifically shown and described herein.
